UNITED STATES PATENT OFFICE.

HENRY W. FALSTROM, OF BLOOMFIELD, NEW JERSEY, ASSIGNOR TO EASTERN TOOL & MFG. CO., OF BLOOMFIELD, NEW JERSEY.

SLIDE.

Application filed March 24, 1927. Serial No. 177,879.

This invention relates to an improved slide for suspender and overall straps and similar articles requiring easy and quick adjustment, the object of the invention being 5 to provide a slide of cheap manufacture which grips the strap firmly, keeps the strap flat and uses a minimum amount of wire.

The invention is illustrated in the accompanying drawing in which Figure 1 is a front view of the improved slide with the strap and a button loop shown in dotted outline. Figure 2 is a section on line 2—2 in Figure 1 and Figure 3 is a section on line 3—3 in Figure 1.

15 The slide is formed of wire and preferably a single piece of wire comprising a central strand 10 with off-set portions 11 near its ends. The said ends are bent back to form loops for the strap and the drawing shows 20 the wire bent into end strands 12 and 13 and then bent to form top and bottom strands 14 and 15 respectively, these terminating in end strands 16 and 17. The end strands are continued so that the ends of the wire are 25 looped as at 18 around the off-set portion 11.

This construction uses a comparatively short length of wire and provides the loops 18 at a point where they form projections near the ends of the slide. These prevent 30 the tendency of the sides of strap 19 from bunching toward the centre of the slide or from bunching at one side which would cause the slide to tilt and the strain would 35 become uneven. The sides of the strap 19 are usually hemmed as at 20 and these

thickened edges assist in holding these edges outside the loops 18 by their engagement with these loops. The loops 18 also hold the slide squarely across the strap when the slide is moved along the strap for adjustment. 40

My manner of threading the strap through the slide is shown in Figure 2, the strap being doubled in the slide and being securely held by engagement with the strands 10, 14 and 15 which prevent slipping. The use of 45 square wire is favored as it assists at its corners in engaging the fabric and holding the strap firmly in adjusted position.

I claim:

1. A slide consisting of a wire formed into 50 the shape of an 8 with the centre strand having off-set portions near the ends thereof, the ends of the wire being bent into loops embracing said off-set portions.

2. A slide consisting of a single piece of 55 wire forming a central strand with off-set portions near its end, the wire being bent back from the ends to form loops and with the ends of the wire returned to form loops embracing said off-set portions. 60

3. A slide consisting of a wire forming a central strand bent to form parallel off-set portions and bent beyond the off-set portions to form top and bottom strands and having the ends of the wire bent parallel with the 65 ends of the central strand and then looped around the off-set portions.

In testimony whereof I affix my signature.

HENRY W. FALSTROM.
